UNITED STATES PATENT OFFICE.

LOUIS KRANZ, OF PROVIDENCE, RHODE ISLAND, ASSIGNOR TO THE WAITE,
THRESHER COMPANY, OF SAME PLACE.

DESIGN FOR A HANDLE FOR BUTTON-HOOKS OR SIMILAR ARTICLES.

SPECIFICATION forming part of Design No. 29,213, dated August 16, 1898.

Application filed July 9, 1898. Serial No. 685,562. Term of patent 3½ years.

To all whom it may concern:

Be it known that I, LOUIS KRANZ, a citizen of the United States, residing at Providence, in the State of Rhode Island, have invented 5 and produced a new and original Design for a Handle for Button-Hooks or Similar Articles, of which the following is a specification, reference being had to the accompanying drawings, forming part thereof.

10 Figure 1 represents the side view of a handle, showing my new design. Fig. 2 represents a central longitudinal section of the same.

15 As shown in the drawings, the leading and material features of my design consist in the circumferentially-beaded end *a*, the elongated beaded panel *b*, the foliated scrolls *c c*, supplemented by the three-leaved ornament

d and inclosing the three-leaved ornament *e*, the oval shield *f*, inclosed by the scrolls *g g*, 20 having rows of beads *h h*, the branching foliated scrolls *i i*, having an inner knurled surface, *j*, the foliated scrolls *k k*, which terminate in the knurled scrolls *l l* and inclose the shell ornament *m*, the tulip-shaped scroll *n*, and the 25 terminal shell ornament *o*.

Having now described my invention, what I claim as new, and desire to secure by Letters Patent, is—

20 The design for the handle of a button-hook 30 or similar article, as herein shown and described.

LOUIS KRANZ.
